UNITED STATES PATENT OFFICE.

WILLIAM C. KENTZER, OF NEW ROCHELLE, NEW YORK.

WINDOW-FASTENING.

1,135,696.

Specification of Letters Patent. Patented Apr. 13, 1915.

Application filed September 26, 1913. Serial No. 791,889.

To all whom it may concern:

Be it known that I, WILLIAM C. KENTZER, a citizen of the United States of America, residing at New Rochelle, county of Westchester, State of New York, have invented certain new and useful Improvements in Window-Fastenings, of which the following is a specification.

This invention relates to an improvement 10 in window sash fastening devices and has for its object the providing of means whereby the sash may be permanently locked in any pre-determined position by means operating from the inside of the window and by 15 locking means operating between the window sash and the strip forming that side of the way in which the window moves toward the inside of the house, thus providing a locking means which cannot be tampered 20 with from the outside of the window without removing the outside window guide and the window sash; in other words, the locking means is protected from external manipulation by reason of the fact that it lies entirely on the inside of the window sash.

The means which I provide to operate the locking means is operated by pressure in the same direction to lock or release the locking device.

30 I am aware that window sash locking devices are known in the art wherein the locking bolt finds its keeper in the external side of the way within which the window frame moves. A serious objection is found in such 35 devices in that this outside strip of the way in which the window moves may be readily tampered with by introducing an instrument between the sash and the outside section of said way for the purpose of manipulating 40 the locking means or said section may be readily broken, thus releasing the locking means, but in the device here described the window sash is interposed between the locking means and the outside so that great difficulty 45 will be found in reaching the locking means from the outside.

In the preferred form of the invention the fastening means consists of a bolt adapted to be projected at right angles to the plane of 50 the glass. This may be conveniently arranged to engage a member rigidly secured to the window frame and covered and protected by the sash itself.

In the device shown, each bolt is actuated 55 by a plurality of members which may be in the form of push buttons, the buttons being

connected to the bolt by separate means so that one serves to advance or project the bolt while the other serves to retract it. The buttons are preferably so arranged that they are 60 operated from the direction in which the bolt is projected, so that both the buttons and the fastening means or bolt and its keeper may be protected to the best advantage, being placed inside the sash and away 65 from the outside of the window.

In the accompanying drawings I have illustrated a preferred form of my invention.

In these drawings—Figure 1 is an elevation of a portion of a window provided with the fastening means of the invention, the greater portion of the window illustrated being broken away for convenience in illustration. Fig. 2 is an elevation of the locking 75 device taken from the inside of the window, the cover of the lock being removed to show the bolt and the mechanism of the lock or projecting and retracting means. Fig. 3 is an elevation of a fragment of the plate in 80 which the bolt sockets are formed. Fig. 4 is a horizontal section through the lower sash, the section being taken through the lock so as to show the bolt and projecting and retracting means. The upper sash is also 85 shown in dotted lines in this figure.

Referring to the drawing by numerals, each of which is used to indicate the same or similar parts in the different figures, I have shown an upper sash 1, a lower sash 2, a fastening device 3 on the lower sash and 4 on the upper sash, and a keeper strip 5 for the lower sash and 6 for the upper sash. The keeper strips are preferably L-shaped in cross-section as shown in Fig. 4, the strip 5 90 for the lower sash being placed with one arm of the L between the lower sash and the retaining strip 7, and the other arm between the retaining strip and the window frame proper 8, the keeper strip 6 for the upper 100 sash, likewise L-shaped in cross-section, having one arm of the L placed on the outer face of the dividing strip 9 and the other arm sunk into the casing or frame proper 8. Both strips or the portion thereof adjacent 105 the sash with which the bolts coöperate are provided with a row of keeper holes 10 adapted to receive the bolt and arranged to conform to the various positions in which it is desired to lock the sash. The locking de- 110 vice proper, indicated by reference character 3 on the lower sash and 4 on the upper

sash, is shown in each instance as contained within a rectangular casing 11 inserted from the running edge 12 of the sash, and seated in an aperture formed in the sash for that purpose. The locks are actuated from the inner face of the sash upon which they are mounted by means of a pair of push buttons 13 coöoperating with each lock, the push buttons in each instance being mounted to slide 5 in apertures 14 in plates 15 set in the sash for that purpose. Each lock, as shown, consists of a bolt 16 suitably mounted to slide in the casing 11 and preferably in a direction parallel to the direction of motion of the actuating members or push buttons 13 and at 10 right angles to the window glass 17.

Each bolt is actuated by a plurality of levers 18 and 19 pivotally mounted in bearings 20 and 21, suitably supported in the 20 lock casing 11 by means of lugs 22 or otherwise, as found most expedient. The levers 18 and 19 are both pivotally or otherwise freely connected to the bolt 16 in any suitable manner as by means of the tongue 23 in the socket 24 in the bolt, the tongue 23 being carried on a cross arm 25 or otherwise on one of the levers 18 which is connected to the lever 19 by means of a pin 26 and jaws 27, or by any suitable pin and slot 30 connection.

The push buttons 13 in the form of the device shown are provided each with a shank 28 pivotally connected at its end as at 29 to the corresponding lever 18 or 19, the important feature of this portion of the device being that one of the buttons engages the lever 18 between its pivot 20 and the bolt 16, while the other of the push buttons 13 engages the lever 19 at a point on the side of 35 its pivot 21 remote from the bolt 16, so that when the push button 13 engaging the lever 19 is depressed or forced inward, the bolt is shot forward, and on the other hand when the push button 13 engaging the lever 18 is 40 forced inward, the bolt is withdrawn.

For convenience in operation in order that each sash may without hesitation or experiment be placed immediately in a position in which the lock will operate, the button plate 50 15 in each instance may be provided with an indicating point 30 and the keeper plates 5 and 6 are provided with corresponding indicating points 31, so placed that when the points 30 and 31 coincide, the bolt 16 will 55 be opposite and in registration with a keeper 10 of the corresponding plate.

It will thus be apparent that either or both sashes may be securely locked in any of a series of positions either open or closed, 60 and the window may thus be utilized for ventilating purposes even when locked to prevent the entrance of intruders, and further that the locking means being in the form of a bolt projected at right angles to 65 the plane of the glass and of the sash, is

caused to enter a concealed and protected keeper member, so that it is extremely difficult for any person desiring to enter from without to gain access to the fastening means and so render it inoperative. Also the push buttons are so placed that they are not only inconvenient of access from without, but are exceedingly difficult of location by any person unfamiliar with the premises. Further the push button operating device described, consisting of two levers of the first and second class, is not only convenient and easy to operate, but simple and reliable.

I have illustrated the locking means 3 as 80 located near the base of the window frame, it will of course be understood that it may be located anywhere within the vertical length of the frame. When it is desired to place the lock at a point where it would be 85 inaccessible to the hand of an intruder when the frame is partly elevated I find it desirable to locate the lock at the top or midway of the frame in which case it will be necessary to shift the position of the keeper plate 90 5 also.

I have thus described specifically a single embodiment of my invention in order that its nature and operation may be clearly understood. However, the specific terms here 95 in are used in their descriptive rather than in their limiting sense and the scope of the invention is defined in the claims.

I claim—

1. A window fastening consisting of a 100 bolt, two levers each being pivotally mounted and connected to the bolt at one end and means engaging each lever for actuating the bolt, one for advancing it and the other for retracting it, one said means engaging 105 one lever between the pivot and the bolt, the other said means engaging the other lever at its extremity beyond the pivot and remote from the bolt.

2. A window fastening consisting of a 110 bolt, two levers each pivotally mounted to swing in the plane of the bolt and connected to the bolt at one end, two push buttons, one for each lever, one for advancing and the other for retracting it, one said button 115 being connected to the one lever between the pivot and the bolt, the other button engaging the other lever at its extremity beyond the pivot and remote from the bolt.

3. A window fastening consisting of a 120 bolt, two levers each pivotally mounted to swing in the plane of the bolt and connected to the bolt at one end, two push buttons, one for each lever, one for advancing and the other for retracting it, one said button being 125 connected to the one lever between the pivot and the bolt, the other button engaging the other lever at its extremity beyond the pivot and remote from the bolt, the connection between the levers and the bolt consisting of a 130

pivotal connection between the end of one lever and the bolt, and a slot and pin connection between the end of the said lever adjacent the bolt and the other lever.

5 4. A window sash suitably mounted to move in ways in combination with a window fastening device mounted on the inside face of the sash comprising a bolt suitably mounted to move at right angles to the plane 10 of the window glass and means to operate

said bolt from the inside of the window, a keeper for said bolt provided in the inside wall of the window sash way, said bolt co-operating with said keeper.

Signed by me at New Rochelle, N. Y. this 15
23d day of September 1913.

WILLIAM C. KENTZER.
